UNITED STATES PATENT OFFICE

90,921

DESIGN FOR A TIRE COVER OR SIMILAR ARTICLE

George Albert Lyon, Asbury Park, N. J., assignor
to Lyon Incorporated, Asbury Park, N. J., a cor-
poration of Delaware

Application September 9, 1932. Serial No. 44,792

Term of patent 14 years

To all whom it may concern:

Be it known that I, **GEORGE ALBERT LYON**, a citizen of the United States, and residing in the city of Asbury Park, in the county of Monmouth and State of New Jersey, have invented a new, original, and ornamental Design for a Tire Cover or Similar Article, of which the following is the specification, reference being had to the accompanying drawing, forming a part thereof.

In the drawing:

Figure 1 is a side elevation of the cover.

Figure 2 is a fragmentary plan or end view of the cover taken on substantially the line II—II

of Figure 1 looking downwardly and showing the corrugations in the rim of the cover.

Figure 3 is an enlarged cross-sectional view taken on the line III—III of Figure 1 in order to more clearly illustrate the outer contour of the cover, but it is to be understood that the present invention resides in the ornamental effect secured by the arrangement of the corrugations in a tire cover as illustrated in Figures 1 and 2.

I claim:

The ornamental design for a tire cover or similar article as shown and described.

GEORGE ALBERT LYON.
